CONTROL APPARATUS FOR TUNING
RADIO RECEIVERS

Alexander W. Plensler, Chicago, Ill., assignor, by
mesne assignments, to Belmont Radio Corpora-
tion, Chicago, Ill., a corporation of Illinois

Application April 24, 1944, Serial No. 532,443

27 Claims. (Cl. 74—10)

1

The present invention relates to control devices and more particularly to improved control apparatus for selectively tuning a radio receiver to desired signal channels.

Various push button actuated mechanically controlled devices are commercially available for selectively actuating the tuning elements of a radio receiver to settings corresponding to particular desired stations. An improved device particularly adapted for this use is disclosed in United States Letters Patent No. 2,243,487, granted May 27, 1941, to the present applicant. This device employs a rotatable tuning shaft having a plurality of heart-shaped cams or control elements spaced axially therealong, which are adapted to be engaged by cam rollers rotatably carried by movable push button actuated manuals arranged transversely of the tuning shaft, the arrangement being such that when any manual is actuated, the associated cam roller and control element are engaged to move the tuning shaft to a setting corresponding to a predetermined signal channel. At one end of the tuning shaft, facilities including a manually operable second shaft extending normal to the tuning shaft through the escutcheon plate of the receiver, are provided for the purpose of manually rotating the tuning shaft to station receiving settings other than those to which the tuning shaft may be operated by the manuals, and for the additional purpose of releasably exerting a clamping force upon the control elements axially of the tuning shaft to permit adjustment of each control element relative to the tuning shaft. Such adjustment is necessary in order accurately to position the control elements for the operation of the tuning shaft to the settings which exactly correspond to the desired signal channels. Releasable clamping arrangements are also described in each of the following Letters Patent of the United States: Morin No. 1,828,197, granted Oct. 20, 1931; Morin No. 1,906,709, granted May 2, 1933; Gersch No. 2,153,865, granted April 11, 1939; Benton No. 2,200,211, granted May 7, 1940; Wells No. 2,214,785, granted Sept. 17, 1940; and Marholz et al., No. 2,330,833, Oct. 5, 1943.

In the specific improved embodiments of these facilities disclosed in the above mentioned Plensler patent, the second shaft is movable axially between a position wherein it is connected to drive the tuning shaft and a position wherein it is connected to drive a traveling nut axially of the tuning shaft to tighten or relieve the clamping force restraining the control elements against movement relative to the tuning shaft.

Functionally, this arrangement has the disadvantage that four unused axial movements of the second shaft are required in each control element resetting operation. This is due partially to the

5 fact that each time the second shaft is moved to a position for rotating the traveling nut the tuning shaft drive connection is broken.

It is an object of the present invention, therefore, to provide improved manual tuning and 10 control element locking facilities of the character described wherein only two axial actuations of the manually operable second shaft are required in a complete control element resetting operation.

15 According to another object of the invention, the improved manual tuning and control element locking facilities are so arranged that each axial movement of the manually operable second shaft is positively used either to clamp or unclamp the 20 control elements, thereby to prevent or permit adjustment of these elements relative to the tuning shaft.

In accordance with a further object of the invention, the clamping and unclamping of the 25 control elements is accomplished without breaking the driving connection between the manually operable second shaft and the tuning shaft.

More generally stated, it is an object of the 30 present invention to provide in a control device of the character described, improved facilities for releasably locking the control elements against movement relative to the tuning shaft, which facilities are of sturdy and cheap construction, and may be easily actuated either to 35 release the control elements for movement relative to the tuning shaft or to positively lock these elements against movement relative to the shaft.

It is a still further and more specific object 40 of the invention to provide an improved rack and pinion assembly for releasably locking the control element of a control device against movement relative to a control shaft, which assembly is operated to lock and release the control elements in response to longitudinal movement of the racks transversely of the control shaft.

The invention, both as to its organization and 45 method of operation, together with further objects and advantages thereof, will best be understood by reference to the specification taken in connection with the accompanying drawings, in which:

Fig. 1 is a side view, partially in section, illustrating improved control apparatus character- 55 ized by the features of the present invention;

Fig. 2 is an under-side view, partially in section, of the apparatus shown in Fig. 1;

Fig. 3 is an end sectional view taken along the lines 3-3 in Fig. 2, illustrating the construction and arrangement of the control elements and associated manuals;

Fig. 4 is an end view of the apparatus shown in Fig. 2, with certain of the parts thereof broken away to facilitate an understanding of the mechanism for manually adjusting the tuning shaft and for releasably locking the control elements against adjustment relative to this shaft;

Figure 5 is a view taken on line 5-5 of Fig. 2;

Fig. 6 is a detail sectional view taken along the lines 6-6 in Fig. 5;

Fig. 7 is a fragmentary view, partially in section, illustrating a modified arrangement of the control apparatus and more particularly the manual tuning and control element locking facilities provided therein;

Fig. 8 is an end view partially in section of the apparatus shown in Fig. 7; and

Figs. 9, 10, 11, 12 and 13 are detail views illustrating certain of the parts embodied in the apparatus shown in Figs. 7 and 8.

Referring now to the drawings, and more particularly to Figs. 1 through 6 thereof, the present improved control apparatus is there illustrated in its embodiment in a radio receiver for the purpose of adjusting the gang connected frequency changing elements which are utilized in a well-known manner to tune the receiver to different signal channels, i. e., to tune the receiver for the reception of signals radiated at different carrier frequencies. More specifically, the frequency changing means of the receiver comprises a pair of tuning condensers 10 carried by a fixed U-shaped supporting frame 13, and having a rotatable shaft 11 which carries the rotor plates of the condensers and may be rotatable through 180° to provide the full tuning range for the receiver. These condensers are electrically included in the receiver circuit in any conventional manner, and the supporting frame 13 therefor is mounted upon the frame 12 of the control or tuning apparatus at one end of this apparatus. The rotor shaft 11 is suitably journaled within bearings carried by the legs of the U-shaped frame member 13 and the parallel extending side parts 12b and 12c of the frame member 12.

The control or tuning shaft 11 also carries a plurality of control or tuning selector elements 14 in the form of heart-shaped cams which are spaced axially along the shaft at the correct points for engagement by cam rollers 16 rotatably supported upon pivotally mounted manuals 15. As best shown in Fig. 3 of the drawings, each manual 15 is in the form of a lever, is pivotally mounted at one end upon a pivot shaft 17, carries a cam actuating roller 16 at its opposite end, and is provided with a manually operable push button 19 extending outward at an angle from one edge thereof. The shaft or pivot rod 17 is supported at its ends by the side parts 12b and 12c of the frame 12, and carries spacing sleeves 18 intermediate the levers 15 for the purpose of maintaining the rollers 16 in transverse alignment with their respective associated cams 14. A second supporting plate 25 is provided at the back side of the longitudinally extending frame part 12a, this supporting plate being provided with a stamped out bumper part 25a, the outer edge of which is disposed in the paths of rotation of the adjacent lever ends. Single turn coil springs 9 wrapped

around the pivot shaft 17, are utilized to bias the levers 15 into engagement with the bumper part 25a. Thus, and as best shown in Fig. 3 of the drawings, a spring 9c individual to the lever 15c is provided for normally biasing this lever against the bumper part 25a so that the roller 16c is out of the path of rotation of the associated cam 14c. One end of this spring is anchored to the extreme right end of the lever 15c and the opposite end thereof is held against unwinding movement through its engagement with the edge of the bumper part 25a. Similar springs 9, individual to the other levers 15, and spaced along the pivot shaft 17 are utilized normally to bias the other levers to engage the bumper part 25a.

The control elements 14 are maintained in spaced-apart relationship axially of the tuning shaft 11 by means of spacing sleeves 20 and friction washers 21, keyed or otherwise locked to shaft 11, the latter elements being utilized to restrain the control elements 14 against movement relative to the shaft 11 when a clamping pressure of suitable magnitude is exerted axially of the shaft upon the stacked elements 14, 20 and 21 in the manner explained below. More specifically, the identified elements are adapted to be clamped by means of the combination manual tuning and control element locking mechanism which is supported upon the frame 12c to the outside thereof, against the end of a sleeve 20a fixedly secured to the shaft 11.

All parts of this mechanism are either carried directly by the shaft 11 at the right end thereof as viewed in Figs. 1 and 2 of the drawings, or upon the legs 26a and 26b of a pair of L-shaped brackets 26, which are rigidly mounted upon the frame part 12c by means of mounting screws 27. Briefly considered, the manual tuning facilities of this mechanism comprise a carriage member 30, slidably supported at the leg ends of the two L-brackets 26; an L-shaped supporting member 31 supported by means of bolts or rivets 32 for limited sliding movement relative to the carriage member 30; a manually operable shaft 50 extending normal to the tuning shaft 11 and journaled for rotation in a bearing member 51 fixedly mounted at the end 31a of the supporting member 31; a long pinion or gear 49 mounted upon the shaft 50 for rotation therewith; and a crown gear 48 fixedly mounted upon the tuning shaft 11 at the right end thereof and having teeth meshing with the teeth of the pinion gear 49 at all positions of the shaft 50 axially of the tuning shaft 11. It will be understood that the push buttons 19 and the shaft 50 are adapted to extend through openings in the escutcheon plate of the receiver for manual actuation from outside of the receiver housing. To facilitate manual rotation of the shaft 50, a knob 53 is mounted upon the projecting end thereof by means of a set screw 54. This shaft and the parts carried thereby are restrained against longitudinal movement relative to the supporting member 31 and the bearing 51 by means of the long pinion 49 and a locking collar 52 which is set screw mounted upon the shaft 50 adjacent the end of the bearing member 51. With this arrangement, the tuning shaft 11 and the various parts carried thereby may be rotated to any desired setting within the limits of the tuning range by appropriate finger manipulation of the knob 53 to rotate the shaft 50 in the desired direction. Thus when this shaft is rotated in either direction, the tuning shaft 11 and the parts carried

thereby are rotated in a corresponding direction through the driving connection afforded by the meshing engagement of the long pinion 49 with the teeth of the crown gear 48.

As indicated above, the facilities for releasably locking or clamping the control elements 14 against rotary movement relative to the tuning shaft 11 are operated in response to longitudinal movement of the shaft 50 transversely of the tuning shaft 11, without breaking the driving connection between the two identified shafts. In brief, these facilities include two relatively rotatable pinions 28 and 29 which are rotatably supported by the tuning shaft 11 intermediate the control element 14f and the crown gear 48; and a pair of rack bars 34 and 35 which are pivotally mounted by means of pivot pins 36 and 37 upon opposite sides of the carriage member 30 and are provided with teeth 43 and 44 normally disengaged from the teeth of the pinion gears 28 and 29 but adapted for engagement with the pinion gear teeth when the carriage member 30 is moved transversely of the tuning shaft 11 by pulling the shaft 50 outwardly from the escutcheon plate of the receiver. In order to effect movement of the pinion 28 axially to the left as viewed in Fig. 2 of the drawings during relative rotary movement of the two pinions 28 and 29 in one direction, thereby to exert the desired clamping pressure upon the control elements 14, the two pinions 28 and 29 are provided with opposed hub portions having meshing cam teeth 28a and 29a, respectively, at the engaging ends thereof. These teeth are provided with flattened ends disposed in planes normal to the tuning shaft 11, which ends are maintained in engagement when the two pinions are rotated to settings wherein the control elements 14 are clamped against rotation relative to the tuning shaft 11. At the left side thereof the pinion 28 is provided with a hub 28b for exerting the required clamping pressure upon the control elements 14 through a pair of sleeves 20b and 21c. In order to maintain a slight clamping pressure upon these control elements when the pinions 28 and 29 are rotated to release these elements for adjustment relative to the shaft 11, a dished spring washer 21d is provided between the two friction washers 21a and 21b.

More specifically to consider the mounting arrangement for the carriage member 30 and the parts supported thereon, it will be noted from a consideration of Figs. 4 and 5 of the drawings, that this member is provided with a central rectangular slot 45 which is in longitudinal alignment with the shaft 50 and the edges of which are disposed within interfitting slots 46a and 46b provided along the opposite side edges of the two L-brackets 26. The end of the tuning shaft 11 projects through the slot 45 to support the crown gear 48 in the manner explained above. Limited sliding movement of the supporting member 31 relative to the carriage member 30 in a direction extending longitudinally of the shaft 50 is obtained by extending the mounting rivets 32 through short elongated slots 33 in the supporting member 31. With this arrangement, the ends of the slots 33 act as stops to define the extent of relative sliding movement between the two members 30 and 31. This relative movement is utilized to move the toothed ends of the two rack bars 34 and 35 toward and away from each other during movement of the carriage member 30 in directions to disengage and engage the rack bar teeth with the teeth of the two pinions 28

and 29. To this end, cam pins 39 and 40 are mounted upon the respective upper ends of the rack bars 34 and 35, as viewed in Figs. 4 and 5 of the drawings, to coact with camming ears 41 and 42 which are bent upwardly and outwardly from the end of the base leg of the supporting member 31 at the opposite edges thereof. More specifically, the pin 40 carried by the rack bar 35 extends through an enlarged opening 40a in the carriage member 30 and bears against the camming edge 42a of the camming ear 42. The camming pin 39, on the other hand, extends directly outward from the rack bar 34 and engages the camming edge 41a of the camming ear 41. For the purpose of normally maintaining the pins 39 and 40 in engagement with the camming edges of the two ears 41 and 42, the downwardly extending ends of these two bars are interconnected by means of a tension spring 41. Thus the bars are biased in a direction to move the toothed ends thereof away from each other and away from the teeth of the pinions 29 and 28.

From the above explanation it will be understood that normally the carriage member 30 and the parts supported thereon occupy the positions illustrated in Fig. 5 of the drawings, that the teeth 43 and 44 of the two rack bars are disengaged from the pinions 29 and 28, and that these two pinions occupy the relative angular settings illustrated in Fig. 1 of the drawings such that the control elements 14 are clamped or locked against rotation relative to the tuning shaft 11. It will be understood also that the control elements occupy different angular positions relative to the tuning shaft 11 such that the tuning condensers 10 may be operated to signal channel settings respectively corresponding to the different control elements through the selective manipulation of the push buttons 19. If, with the apparatus in the condition just described, it is desired to tune the receiver for the reception of the particular signal corresponding to the push button 19c, for example, this button may be pushed downwardly from the position illustrated in Fig. 3 of the drawings to bring the cam roller 15c into engagement with the camming surface of the control element 14c.

During continued movement of the parts 19c, 16c and 15c toward the tuning shaft 11, the engaged roller 16c and control element 14c coact to rotate the tuning shaft 11 to the particular angular setting corresponding to the desired signal channel. This tuning position of the shaft is reached when the roller 16c is moved to engage the low point of the cam 14c. After it is reached, the push button 19c may obviously be released to return to its normal position under the influence of the biasing spring 9c. In a manner entirely similar to that just described, the other push buttons 19 may be selectively actuated for the purpose of selectively tuning the receiver to the other signals to which these push buttons respectively correspond. Tuning of the receiver to a signal within the signal reception band of the receiver, but not corresponding to one of the push buttons 19, is accomplished through manual actuation of the knob 53 in the manner explained above.

As previously indicated, in order to adjust the angular settings of the control elements 14 relative to the tuning shaft 11, thereby to change the signal channels to which these elements are respectively capable of tuning the receiver, the clamping pressure exerted axially of the shaft 50 upon the control elements 14 is partially released.

To this end, the knob 53 is pulled outwardly from the escutcheon plate of the receiver, thereby to move the carriage member 30 and the parts carried thereby transversely of the tuning shaft 11 in a direction to rotate the pinions 28 and 29 so that the cam teeth 43 and 44 thereof are brought into full meshing engagement. Throughout such transverse movement of the carriage member 30, the long pinion 49 is obviously maintained in meshing engagement with the crown gear 48. During the initial outward movement of the knob 53 and the parts 50, 49 and 31, the carriage member 30 remains stationary, due to the pin and slot connection between the two parts 30 and 31. Incident to this relative movement between the identified parts of 30 and 31, the cam ears 41 and 42 are withdrawn from the pins 39 and 40 permitting the rack teeth 43 and 44 to move away from each other under the influence of the spring 47. The purpose of this limited pivotal movement of the rack bars 34 and 35 during the initial pulling movement on the knob 53 is to prevent the leading teeth of the two rack bars from lockingly engaging displaced teeth of the two pinions 28 and 29 and to insure the same pinion tooth displacement between the leading teeth of the two rack bars during successive operations of the carriage member 30 to release the clamping pressure from the control elements 14. In this regard it will be understood that should the leading rack bar tooth 43a, for example, engage the end of the tooth 29b and the leading tooth of the rack bar 35 engage the end of a similarly positioned tooth on the pinion 28, with no facilities for pivotal movement of the two rack bars 34 and 35, a locking connection would be set up between the two rack bars 34 and 35 through the pinions 28 and 29 and the shaft 11 which would positively prevent further transverse movement of the carriage member 30 and parts carried thereby. The limited pivotal movement of the two bars 34 and 35 permits the leading teeth of the rack bars to ride over or not engage the ends of the wrong pinion teeth and insures the same pinion tooth displacement between the leading rack bar teeth during successive transverse movements of the carriage member 30 to the control element release position.

After the lost motion between the two parts 30 and 31 has been taken up in the manner just explained, the carriage member 30 and the two rack bars 34 and 35 are moved with the parts 31 and 50 during the continued movement of the parts outwardly from the shaft 11. Accordingly, the teeth 43 and 44 are moved into meshing engagement with the teeth of the pinions 28 and 29, following which these pinions are rotated relative to each other in the proper directions to bring the cam teeth 28a and 29a into full meshing engagement. As these cam teeth are brought into mesh, the spring washer 21d acts to move the pinion 28 along the shaft to the right as viewed in Figs. 1 and 2 of the drawings, thereby to relieve the clamping pressure exerted upon the control elements 14 axially of the shaft through the spacing sleeves 20. Thus the control elements 14 are released for adjustment relative to the shaft 11.

Following the operations just described, the control element 14a, for example, may be set to a new angular position relative to the shaft 11, so that it will coat with the manual 19a and its associated parts to tune the receiver for the reception of a different desired signal. To this end, the knob 53 is first used to manually tune the receiver to the desired signal frequency. After the

desired signal has thus been selected, the knob 53 is held against further rotation, and the manual 19a is actuated for the purpose of rotating the control element 14a to the new setting relative to the shaft 11. After the new setting is thus established, the manual 19a may be released. In a manner entirely similar to that just described, any one or all of the remaining five control elements may be set to new positions relative to the shaft 11. In this regard, it is pointed out that the spring washer 21d maintains sufficient axial pressure upon the control elements to prevent the same from being rotated relative to the friction washers 21 keyed to the shaft 11 otherwise than in the manner just described. In other words, the spring 21d prevents the desired angular settings of the control elements relative to the shaft 11 from being disturbed when once established.

After all of the control elements have been adjusted in the manner explained above, they may be relocked against movement relative to the shaft 11 by pushing upon the knob 53 to move the carriage member 30 and the parts carried thereby back to their respective normal positions. During the initial backward movement of the supporting member 31, the carriage member 30 remains stationary and the cam ears 41 and 42 coat with the cam pins 39 and 40 to rotate the toothed ends of the rack bars 34 and 35 toward each other, thereby to move the teeth 43 and 44 into deeper meshing engagement with the teeth of the pinions 28 and 29. After the lost motion between the two members 31 and 30 is taken up, these two members move in unison, thereby reversely to rotate the two pinions 28 and 29 relative to each other until the cam teeth respectively carried thereby are engaged only at their flattened ends in the manner shown in Fig. 1 of the drawings. Incident to the described relative movement of the cam teeth 28a and 29a, the pinion 28 is moved axially to the left to flatten the spring washer 21d and thus increase the clamping pressure exerted upon the control elements 14 sufficiently to lock these elements against rotation relative to the shaft 11. During the final movement of the carriage member 30 and its associated parts back to their respective normal positions, the teeth 43 and 44 of the rack bars 34 and 35 are disengaged from the teeth of the pinions 29 and 28, thereby to free the tuning shaft 11 and the control elements carried thereby for unrestricted rotation.

From the above explanation, it will be understood that the clamping facilities may be actuated to release the control elements 14 for adjustment to any desired angular position relative to the shaft 11. This is accomplished by utilizing reverse longitudinal movement of the carriage member 30 and the parts carried thereby, to effect reverse rotation of the two locking pinions 28 and 29. This arrangement is to be distinguished from conventional locking mechanism wherein the tuning shaft must be rotated to a stop position at one end of the tuning range before the locking or clamping mechanism can be actuated to release the control elements for adjustment relative to the tuning shaft, and the tuning shaft must be rotated to the opposite stop position at the other end of the tuning range before the locking or clamping mechanism can be actuated to reclamp or relock the control elements against movement relative to the tuning shaft. It will also be noted that in the improved mechanism described above, each movement of the second shaft 50 is positively utilized to per-

form a definite function. In other words, unnecessary movements of this shaft are entirely eliminated in the operation of the mechanism to perform the functions assigned thereto.

These same operating characteristics are also embodied in the modified arrangement illustrated in Figs. 7 through 13 of the drawings, wherein like reference numerals have been used to identify corresponding parts. In a functional sense, the modified mechanism is the exact equivalent of that illustrated in Figs. 1 through 6 of the drawings and described above. Structurally, however, the modified arrangement illustrated in Figs. 7 through 13 of the drawings is substantially different from the first described structure. More in detail, the supporting bracket 26 of the modified structure is provided with four equiangularly spaced legs which respectively terminate in outwardly extending supporting parts 26c, 26e, 26g and 26h, these parts being located at different distances from the base of the bracket 26 in order to provide for the required spacing of the rack bars 34 and 35 axially of the shaft 11 in alignment with the teeth of the pinions 29 and 28. This bracket slidably supports the supporting member 31 which includes stepped but parallel extending legs 31c and 31d slidably engaging the parts 26g and 26h of the bracket 26. The two leg parts 31c and 31d are respectively slotted at 31e and 31f to receive headed assembly rivets or screws 32a and 32b, which are rigidly mounted within openings through the bracket parts 26g and 26h. The slidable support for the member 31 also comprises a part 31b which projects from the member 31 and is slotted along the opposite edges thereof as indicated at 31g to interfit with the edges of a channel 26d cut in the bracket part 26c. Thus a three-point sliding support is provided for mounting the supporting member 31 upon the bracket 26 for movement transversely of the tuning shaft 11.

The rack bars 34 and 35 are of L-shaped configuration, being pivotally and slidably supported at their base leg ends upon the stepped part 26e of the bracket 26. More specifically, the base legs of the two rack bars are disposed upon opposite sides of the bracket part 26e and are pivotally interconnected at their ends by means of a pivot pin 60 which is slidable within a slot 26f cut in the identified bracket part. Rubber friction washers 61 disposed upon opposite sides of the bracket part 26e and carried by the pivot pin 60 are utilized to space the rack bars apart the required distance to align the teeth 43 and 44 thereof with the pinions 29 and 28. Lost motion means are utilized to interconnect the opposite ends of the rack bars 34 and 35 with the legs 31c and 31d of the supporting member 31. More specifically, pins 62a and 62b are respectively mounted upon the two legs 31d and 31c to coact with angularly extending slots 63a and 63b in the rack bars 34 and 35 for the purpose of moving the teeth of these bars toward and away from each other during movement of the supporting member 31 transversely of the tuning shaft 11. The rubber friction washers 61 supply the required frictional drag to resist movement of the rack bars transversely of the shaft 11 and thus insure operation of the camming means to move the toothed ends of the bars toward and away from each other during movement of the carriage means transversely of the shaft. Thus, the pin and slot connections 62 and 63 perform the same function in the mechanism disclosed in Figs. 7 and 8 as do the cam ears 41 and 42, and pins 39

and 40 in the mechanism shown in Figs. 1 through 6, inclusive.

The manually operable second shaft 50 of the mechanism shown in Figs. 7 and 8 is provided with an end portion of reduced diameter which is journaled in a bearing sleeve 51 rigidly mounted within an opening through a supporting panel 64. This panel is in turn rigidly mounted upon the supporting member 31. At its inner end, the shaft 50 carries the long pinion 49 which meshes with the crown gear 48 to provide a driving connection between the two shafts 50 and 11 at all positions of the supporting member 31 transversely of the tuning shaft 11. The pinions 28 and 29 are provided with axially disposed cam teeth 28a and 29a for supplying the required axial thrust upon the spacing sleeves 20 and friction washers 21 to restrain the control elements 14 against rotary movement relative to the shaft 11. Here again, the ends of the teeth 28a and 29a are flattened so that relative movement between the two pinions is prevented when these pinions occupy positions wherein the control elements 14 are clamped against rotation relative to the shaft 11. The shaft 11 is threaded at the end upon which the crown gear 48 is mounted, in order to receive a nut 65 which is utilized to fix the initial positions of the pinions 28 and 29 along the shaft 11. The thrust normally exerted upon the control elements 14 through the sleeves 20 and the washers 21 is thus determined by the setting of the nut 65 along the shaft 11, and may obviously be adjusted as desired by setting the nut 65 at different positions axially along this shaft. Once the desired nut position is established, the crown gear 48 is set screw mounted upon the projecting end portion of the shaft, thereby to prevent inadvertent travel of the nut 65 toward the shaft end.

As indicated above, the modified mechanism just described is functionally equivalent to the first embodiment of the invention as disclosed in Figs. 1 to 6, inclusive, of the drawings. In this regard, it will be understood that with the parts of the modified mechanism occupying the positions illustrated in Figs. 7 and 8 of the drawings, the knob 53 may be rotated at will for the purpose of actuating the shaft 11 to any desired tuning position. It will be understood further, that when the knob 53 is pulled outwardly from the shaft 11, the supporting member 31 and the rack bars 34 and 35 are moved transversely of the shaft causing the teeth of the rack bars to engage the pinions 28 and 29 to rotate these pinions relative to each other until the cam teeth 28a and 29a are in full meshing engagement, thereby to release the axial thrust holding the control elements against adjustment relative to the shaft 11. When these elements have been set in the desired adjusted positions relative to the shaft 11, the knob 53 may be pushed inwardly causing the rack bars 34 and 35 to reversely rotate the pinions for the purpose of re-establishing the clamping pressure upon the control elements. During the forward movement of the member 31 relative to the support bracket 26 the pins 62a and 62b coact with the cam slots 63a and 63b to move the rack bar teeth 43 and 44 away from the shaft 11, thereby to prevent the establishment of a binding or locking connection which might prevent meshing engagement of the teeth with the pinion teeth, and to insure the same pinion tooth displacement between the leading rack bar teeth during successive engagements of these teeth with the pinions. Converse-

11

ly, during backward movement of the member 31 transversely of the shaft 11, the pins 62a and 62b coat with the slots 63a and 63b to produce full meshing engagement of the rack bar teeth 43 and 44 with the engaged pinion teeth, thereby to insure the required relative rotation of the pinions 28 and 29 to move these pinions back to the relative positions illustrated in Fig. 7 of the drawings.

While two embodiments of the invention have been disclosed, it will be understood that various modifications may be made therein without departing from the spirit and scope of the invention as defined in the appended claims.

I claim:

1. In radio tuning apparatus which includes a tuning shaft rotatable through a desired tuning range and a plurality of tuning selector elements carried by said shaft and releasably restrained against movement relative to said shaft; a manually operable element, means supporting said element for two characteristic types of movement, means for rotating said shaft to any setting within said range in response to a corresponding movement of said manually operable element of one of said types, and means responsive to movement of said manually operable element of the other of said types for releasing said selector elements for movement relative to said shaft.

2. In radio tuning apparatus which includes a tuning shaft rotatable through a desired tuning range between predetermined stop settings and a plurality of tuning selector elements carried by said shaft and releasably restrained against movement relative to said shaft; a manually operable shaft, means supporting said manually operable shaft for rotary and axial movement, means responsive to rotation of said manually operable shaft for rotating said tuning shaft to different settings within said tuning range, and means responsive to axial movement of said manually operable shaft for releasing said selector elements for movement relative to said tuning shaft.

3. In radio tuning apparatus which includes a tuning shaft rotatable through a desired tuning range between predetermined stop settings and a plurality of tuning selector elements carried by said shaft and releasably restrained against movement relative to said shaft; a manually operable shaft, means supporting said manually operable shaft for rotary and axial movement, means responsive to rotation of said manually operable shaft for rotating said tuning shaft to different settings within said tuning range, and means operative in response to movement of said manually operable shaft axially in one direction for releasing said elements for movement relative to said tuning shaft and operative in response to movement of said manually operable element axially in the reverse direction for again restraining said selector elements against movement relative to said shaft.

4. In radio tuning apparatus which includes a tuning shaft rotatable through a desired tuning range and a plurality of tuning selector elements carried by said shaft and releasably restrained against movement relative to said shaft; a manually operable element, means supporting said element for two characteristic types of movement, means interconnecting said shaft and said manually operable element to provide a driving connection for rotating said shaft to different settings within said range in response to movement of said manually operable element of one of said types, and means responsive to movement

12

of said manually operable element of the other of said types for releasing said selector elements for movement relative to said shaft without breaking the driving connection between said manually operable element and said shaft.

5. In radio tuning apparatus which includes a tuning shaft rotatable through a desired tuning range and a plurality of tuning selector elements carried by said shaft and releasably restrained against movement relative to said shaft; a second shaft, means supporting said second shaft for rotary and axial movement, interengaged and relatively movable driving parts interconnecting said shafts to rotate said tuning shaft to different settings within said range in response to rotation of said second shaft, and means responsive to axial movement of said second shaft for releasing said selector elements for movement relative to said shaft without disengaging said relatively movable parts to break the driving connection between said shafts.

6. In radio tuning apparatus which includes a tuning shaft rotatable through a desired tuning range and a plurality of tuning selector elements carried by said shaft and releasably restrained against movement relative to said shaft; a second shaft, means supporting said second shaft for rotary and axial movement, interengaged and relatively movable driving parts interconnecting said shafts at all axial settings of said second shaft to provide a connection for rotating said tuning shaft in response to rotation of said second shaft, and restraining means controlled by axial movement of said second shaft for releasably restraining said tuning shaft and said selector elements against relative movement.

7. In radio tuning apparatus which includes a tuning shaft rotatable through a desired tuning range and a plurality of tuning selector elements carried by said shaft; a second shaft disposed at an angle relative to said tuning shaft, means supporting said second shaft for rotary and axial movement, a crown gear fixedly mounted upon said tuning shaft, an elongated pinion fixedly mounted upon said second shaft and meshing with said crown gear in all axial settings of said second shaft, whereby said tuning shaft may be rotated to different settings within said tuning range by rotating said second shaft regardless of the axial setting of said second shaft, and restraining means controlled by axial movement of said second shaft for releasably restraining said tuning shaft and said selector elements against relative movement.

8. In radio tuning apparatus which includes a tuning shaft rotatable through a desired tuning range and a plurality of tuning selector elements carried by said shaft, a carriage movable transversely of said shaft, a second shaft rotatably supported by said carriage, interengaged and relatively movable driving parts interconnecting said shafts at all transverse settings of said carriage to provide a connection for rotating said tuning shaft in response to rotation of said second shaft, interengageable parts respectively supported by said carriage and said tuning shaft for movement into and out of engagement in response to movement of said carriage transversely of said tuning shaft, and means controlled by movement of said last-named parts when engaged for releasably restraining said tuning shaft and said selector elements against relative movement.

9. In radio tuning apparatus which includes a tuning shaft rotatable through a desired tuning

range and a plurality of tuning selector elements carried by said shaft, a carriage movable transversely of said shaft, a second shaft rotatably supported by said carriage, interengaged and relatively movable driving parts interconnecting said shafts at all settings of said carriage to provide a connection for rotating said tuning shaft in response to rotation of said second shaft, a pair of pinions supported upon said tuning shaft for relative rotary movement, cam means controlled by relative rotary movement between said pinions for releasably restraining said tuning shaft and said selector elements against relative movement, and rack means carried by said carriage and engageable with said pinions to move said cam means between selector element release and selector element restraining settings in response to movement of said carriage transversely of said tuning shaft.

10. In radio tuning apparatus which includes a tuning shaft rotatable through a desired tuning range and a plurality of tuning selector elements carried by said shaft, a carriage movable transversely of said shaft, a second shaft rotatably supported by said carriage, interengaged and relatively movable driving parts interconnecting said shafts at all settings of said carriage to provide a connection for rotating said tuning shaft in response to rotation of said second shaft, a pair of pinions supported upon said tuning shaft for relative rotary movement, cam means controlled by relative rotary movement between said pinions for releasably restraining said tuning shaft and said selector elements against relative movement, a pair of rack bars pivotally supported by said carriage and respectively engageable with said pinions upon opposite sides of said tuning shaft to move said cam means between selector element release and selector element restraining settings in response to movement of said carriage transversely of said tuning shaft, and means co-acting with said rack bars for insuring the same pinion tooth displacement between the leading teeth of said rack bars and the teeth of said pinions during successive operations of said carriage to effect the release of said selector elements.

11. In a control device which includes a plurality of control elements carried by a rotatable shaft; cam means rotatably supported by said shaft to exert a restraining force upon said elements, said cam means and said shaft being relatively rotatable between positions wherein said elements and said shaft are relatively movable and are restrained against relative movement, carriage means movable transversely of said shaft and including rack means operative to produce relative movement between said shaft and said cam means during such transverse movement, and means including an element rotatably supported by said carriage means for rotating said shaft and control elements in unison in at least one position of said carriage means.

12. In a control device which includes a plurality of control elements carried by a rotatable shaft; a pinion rotatably supported by said shaft, cam means rotatable with said pinion and operative to exert a restraining force upon said elements, said cam means being rotatable relative to said shaft by said pinion between positions wherein said elements and said shaft are relatively movable and are restrained against relative movement, carriage means movable transversely of said shaft, a rack bar pivotally supported by said carriage means and operative to engage said

pinion to rotate said pinion and cam means relative to said shaft during movement of said carriage means transversely of said shaft, and means including an element rotatably supported by said carriage means for rotating said shaft and control elements in unison in all positions of said carriage means transversely of said shaft.

13. In a control device which includes a plurality of control elements carried by a rotatable shaft; a pinion rotatably supported by said shaft, cam means rotatable with said pinion and operative to exert a restraining force upon said elements, said cam means being rotatable relative to said shaft by said pinion between positions wherein said elements and said shaft are relatively movable and are restrained against relative movement, carriage means movable transversely of said shaft, a rack bar pivotally supported by said carriage means and operative to engage said pinion to rotate said pinion and cam means relative to said shaft during movement of said carriage means transversely of said shaft, and means interconnecting said rack bar and a part of said carriage means for pivoting the toothed end of said rack bar away from said shaft before said rack bar and pinion are engaged.

14. In a control device which includes a plurality of control elements carried by a rotatable shaft; a pair of pinions rotatably supported by said shaft, cam means disposed between said pinions for actuation in response to relative rotation of said pinions and operative to exert a restraining force upon said elements, said cam means being movable between positions wherein said elements and said shaft are relatively movable and are restrained against relative movement in response to relative rotation of said pinions in reverse directions, carriage means movable transversely of said shaft, rack bars pivotally supported by said carriage means and operative to engage said pinions upon opposite sides of said shaft, thereby to produce relative rotation of said pinions in opposite directions in response to reverse transverse movements of said carriage means, and means including an element rotatably supported by said carriage means for rotating said shaft and control elements in unison in all positions of said carriage means transversely of said shaft.

15. In a control device which includes a plurality of control elements carried by a rotatable shaft; a pair of pinions rotatably supported by said shaft, cam means disposed between said pinions for actuation in response to relative rotation of said pinions and operative to exert a restraining force upon said elements, said cam means being movable between positions wherein said elements and said shaft are relatively movable and are restrained against relative movement in response to relative rotation of said pinions in reverse directions, carriage means movable transversely of said shaft, rack bars pivotally supported by said carriage means and operative to engage said pinions upon opposite sides of said shaft, thereby to produce relative rotation of said pinions in opposite directions in response to reverse transverse movements of said carriage means, and means interconnecting said rack bars and a part of said carriage means to permit limited relative movement between each of said rack bars and said carriage means, thereby to prevent locking engagement between the leading teeth of said rack bars and the respective corresponding teeth of said pinions during the initial

Engagement of said leading rack bar teeth with the corresponding teeth of said pinions.

16. In a control device, a shaft, a pair of pinions rotatably supported by said shaft, control means carried by said shaft, mechanism responsive to relative rotary movement between said pinions for controlling said control means, carriage means movable transversely of said shaft, rack bars pivotally supported by said carriage means and operative to engage said pinions upon opposite sides of said shaft, thereby to produce relative rotation of said pinions in opposite directions in response to reverse transverse movements of said carriage means, and means responsive to each of successive movements of said carriage means in a direction to engage said rack bars and pinions for moving the leading teeth of said rack bars away from each other before they are moved into meshing engagement with the teeth of said pinions, thereby to prevent locking engagement between said leading teeth of said rack bars and the respective corresponding teeth of said pinions during the initial engagement of said leading rack bar teeth with the corresponding teeth of said pinions.

17. In a control device, a shaft, a pair of pinions rotatably supported by said shaft, control means carried by said shaft, mechanism responsive to relative rotary movement between said pinions for controlling said control means, carriage means movable transversely of said shaft, rack bars pivotally supported by said carriage means and operative to engage said pinions upon opposite sides of said shaft, thereby to produce relative rotation of said pinions in opposite directions in response to reverse transverse movements of said carriage means, and means responsive to each of successive back and forth movements of said carriage means for moving the leading teeth of said rack bars away from each other before they are moved to mesh with the teeth of said pinions each time said carriage means is moved in a direction to engage said rack bars and pinions and for moving said leading teeth of said rack bars toward each other during the reverse movement of said carriage means, thereby to prevent locking engagement between said leading teeth of said rack bars and the respective corresponding teeth of said pinions during the initial engagement of said leading rack bar teeth with the teeth of said pinions and to provide for the same pinion tooth displacement between said leading rack bar teeth during repeated engagement of said leading rack bar teeth with the teeth of said pinions.

18. In a control device, a shaft, a pair of pinions rotatably supported by said shaft, control means carried by said shaft, mechanism responsive to relative rotary movement between said pinions for controlling said control means, carriage means movable transversely of said shaft and comprising two relatively movable parts, rack bars pivotally supported by one part of said carriage means and operative to engage said pinions upon opposite sides of said shaft, thereby to produce relative rotation of said pinions in response to transverse movement of said carriage means, and camming means operative in response to the relative movement between said parts which occurs during transverse movement of said carriage means for moving the leading teeth of said rack bars away from each other before they are moved to mesh with the teeth of said pinions.

19. In a control device, a shaft, a pair of pinions rotatably supported by said shaft, control means carried by said shaft, mechanism responsive to

relative rotary movement between said pinions for controlling said control means, carriage means movable transversely of said shaft and comprising two relatively movable parts, rack bars pivotally supported by one part of said carriage means and operative to engage said pinions upon opposite sides of said shaft, thereby to produce relative rotation of said pinions in response to transverse movement of said carriage means, spring means tending to pivot the toothed portions of said rack bars away from each other, and camming means operative in response to the relative movement of said carriage means for permitting the leading teeth of said rack bars to move away from each other before they are moved to mesh with the teeth of said pinions.

20. In a control device, a shaft, a pinion rotatably supported by said shaft, control means carried by said shaft, mechanism responsive to relative rotary movement between said pinion and said shaft for controlling said control means, carriage means movable transversely of said shaft, a rack bar pivotally supported by said carriage means and operative to engage said pinion, thereby to produce relative rotation between said pinion and said shaft, in response to movement of said carriage means transversely of said shaft, and means responsive to movement of at least a part of said carriage means in a direction to engage said rack and pinion for pivoting said rack bar relative to said carriage means in a direction to move the leading tooth of said rack bar away from said shaft as said rack bar teeth are moved into meshing engagement with said pinion.

21. In a control device, a shaft, a pinion rotatably supported by said shaft, means carried by said shaft and controlled by relative rotary movement between said pinion and said shaft, carriage means movable transversely of said shaft and comprising two relatively movable parts, a rack bar pivotally supported by one part of said carriage means and operative to engage said pinion during movement of said carriage means transversely of said shaft, thereby to produce relative rotation between said pinion and said shaft, and means including camming means operative in response to the relative movement which occurs between said parts during transverse movement of said carriage means for pivoting said rack bar to move the leading tooth of said rack bar away from said shaft before said rack bar teeth are moved into meshing engagement with said pinion.

22. In a control device, a support, a shaft rotatably carried by said support, a pair of pinions rotatably supported by said control shaft, means carried by said shaft and controlled by relative rotary movement between said pinions, rack bars movable transversely of said shaft and disposed to engage said pinions upon opposite sides of said shaft, thereby to produce relative movement between said pinions when moved transversely of said shaft, friction drag means slidably interconnecting said rack bars and said support, a member slidably carried by said support to move said bars back and forth transversely of said shaft, and cam means interconnecting said bars and said member to move said rack bars apart as said member is moved to engage said bars and pinions and to move said bars toward each other as said member is moved to disengage said bars and pinions.

23. In a control device which includes a plurality of control elements carried by a shaft; the

means for releasably holding said elements in adjusted positions along said shaft which comprises restraining means rotatably supported by said shaft to exert a restraining force upon said elements, said restraining means and said shaft being relatively rotatable between positions wherein said elements are movable relative to said shaft and are restrained against movement relative to said shaft, and means including a toothed member movable transversely of said shaft to engage said restraining means for producing relative movement of said shaft and said restraining means between said two positions.

24. In a control device which includes a plurality of control elements carried by a shaft, a pair of pinions rotatably carried by said shaft, means normally restraining said elements against movement relative to said shaft and operative to release said elements for movement relative to said shaft in response to relative rotation of said pinions, and rack bars engageable with said pinions upon opposite sides of said shaft and movable transversely of said shaft to engage said pinions and then produce relative rotary movement therebetween.

25. In a control device which includes a plurality of control elements carried by a shaft, a pair of pinions rotatably carried by said shaft to exert an axially directed clamping pressure upon said elements, means for moving at least one of said pinions axially of said shaft to relieve the clamping pressure upon said elements in response to rotation of said pinions relative to said shaft, and rack means engageable with said pinions and movable transversely of said shaft to 35

engage said pinions and then rotate said pinions about said shaft.

26. In a control device which includes a plurality of control elements carried by said shaft, 5 a pair of pinions rotatably carried by said shaft to exert an axially directed clamping pressure upon said elements, means for moving at least one of said pinions axially of said shaft to relieve the clamping pressure upon said elements in response to opposite rotation of said pinions relative to said shaft, and rack bars engageable with said pinions upon opposite sides of said shaft and movable transversely of said shaft to engage said pinions and then produce opposite rotation of said pinions about said shaft.

27. In a control device which includes a plurality of control elements carried by said shaft, a pair of pinions rotatably carried by said shaft to exert an axially directed clamping pressure upon said elements, means for moving at least one of said pinions axially of said shaft to relieve the clamping pressure upon said elements in response to opposite rotation of said pinions relative to said shaft, a member movable transversely of said shaft and provided with off set rack elements overlying said pinions upon opposite sides of said shaft, said rack elements including teeth engageable with said pinions upon movement of said member transversely of said shaft, whereby said pinions are oppositely rotated to release said control elements for movement relative to said shaft in response to movement of said member transversely of said shaft.

ALEXANDER W. PLENSLER.
